Assistant Examiner — Sloan Rozin

(74) Attorney, Agent, or Firm — Lowry Blixseth LLP;
 Scott M. Lowry(57) **CLAIM**

The ornamental design for a sign panel, as shown and described.

DESCRIPTION

FIG. 1 is a perspective view showing the front, top and right sides of the sign panel;

FIG. 2 is a front elevation view of the sign panel, the rear elevation view being identical;

FIG. 3 is a right side elevation view of the sign panel, the left side elevation view being a mirror image thereof; and,

FIG. 4 is a top plan view of the sign panel.

The bottom plan view is plain and unornamental and not part of the claimed design.

1 Claim, 4 Drawing Sheets(56)
